Erwin Maurer,
Frederick S. Winters
Attorney

UNITED STATES PATENT OFFICE.

ERWIN MAURER, OF JAMAICA, NEW YORK.

BROODER.

1,275,065.

Specification of Letters Patent.

Patented Aug. 6, 1918.

Application filed July 3, 1917. Serial No. 178,355.

To all whom it may concern:

Be it known that I, ERWIN MAURER, a citizen of the United States, residing at Jamaica, Long Island, in the county of 5 Queens and State of New York, have invented certain new and useful Improvements in Brooders, of which the following is a full, clear, and exact specification.

This invention relates to brooders, and has 10 for one of its objects to produce a brooder which may be easily knocked down for storing or transportation.

Another object is to provide a brooder composed of detachable parts held together 15 without bolts or other permanent fastening means. A further object is to provide a sectional brooder which may be extended at will by the use of additional sections to produce a brooder of any desired capacity.

20 Other objects will appear as the description proceeds.

The invention will be first hereinafter described in connection with the accompanying drawings, which constitute part of this 25 specification, and then more specifically defined in the claims at the end of the description.

In the accompanying drawings, wherein similar reference characters are used to 30 designate corresponding parts throughout the several views:—

Figure 1 is a central longitudinal vertical section through a brooder constructed substantially in accordance with this invention, on the line I—I of Fig. 2.

Fig. 2 is an end elevation of the brooder.

Fig. 3 is a section on the line III—III of Fig. 1.

Fig. 4 is a detailed view of the partition, 40 and

Fig. 5 is a broken side elevation of the adjacent end portions of two brooder sections of the type shown in the other figures, illustrating how they may be connected with 45 a single heating device.

The side walls and top of the brooder are formed by a curved member 1 which is preferably made in sections, each of which extends from side to side and from one end 50 piece 3 to a partition 8. Along one edge of each cover section 1 there is a continuous depending rib 2 adapted to fit into a corresponding groove 5 in the edge of the end piece 3, while along the other edge of said 55 cover section a similar depending rib 11 is carried for engagement with one of a pair

of spaced grooves 10 in the edge of the partition 8. When the cover sections are placed in the position illustrated in Fig. 1, with the ribs 2 and 11 engaging the grooves 5 and 10, respectively, the adjacent edges of said cover sections will meet, and either of said cover sections may be lifted off to permit access to the interior of the brooder without the necessity of removing screws, bolts or other 60 fastening means.

Each end piece 3 is made in two parts, the lower part 4 being connected to the upper part by tongue and groove 6. The lower part 4 has a base flange 7 by which 70 the end piece is supported in upright position. The partition 8 is similarly provided with a base flange 9 for the same purpose.

At the joint between the two parts of the end piece there is formed a passage 19 for 75 the end portion 18 of a heating pipe which interiorly of the brooder has two branches 17 extending longitudinally thereof. Passages for said branches 17 are formed at 12 in the partition 8 by cutting in from the 80 lower edge thereof to provide doorways 13 allowing communication from one side of the partition to the other, and leaving flaps 15 separated by a slot 16 between said doorways and passages 12. Said flaps 15 may 85 be bent out of the way when the branches 17 of the heating pipe are to be inserted into the passages 12 or removed therefrom, and when the pipe is in position said flaps are in the position shown in Fig. 4 in which they 90 support the pipe at the same level with the passages 19 in the end pieces. Doors 14 may be used for closing the doorways 13. The partition is further provided with a plurality of openings 44 permitting heat to 95 pass freely from one side to the other, so that a single thermostat 34 mounted in one compartment of the brooder will suffice to regulate the temperature therein. The thermostat is connected to a rod 33 extending 100 through the top of the brooder, and said rod is pivoted at 32 to one end of a lever 30 fulcrumed at 31 and connected at the other end to a vent cap 29.

As illustrated in Fig. 1, a single brooder 105 may be heated by a burner 24 supplied with fluid fuel from a tank 25 and housed in a casing 22 having air inlet openings 23. The heat from the burner passes to the pipe 18 through an elbow 26 which is hinged at 27 110 to said pipe, so that it may be swung upward when it is necessary to light or extin-

guish the burner. The opposite end of the pipe 18 is closed by a cap 20 preferably having a small opening 21 therein to allow the dead heat to escape.

5 Two brooders may be heated from a single-burner 39, as illustrated in Fig. 5, by substituting for the elbow 26 of Fig. 1, an upright pipe 36 having oppositely extending branches 35 connected to the pipes 17 of the 10 two brooders. The burner 39 is housed in a casing 37 provided with air inlet openings 38, and the pipe 36 has an opening 42 adapted to be closed by a door 43, whereby access may be had to the burner. A heat 15 dome 41 is arranged above the branch pipes 35 and in vertical alinement with the pipe 36, to insure a proper circulation of the heated air to either side. The burner 39 may be supplied with fluid fuel from a tank 40.

20 Having thus described my invention, what I claim as new and desire to secure by Letters Patent of the United States is:—

1. A knockdown brooder comprising end pieces having grooves in their edges, a par-

tition having a pair of grooves in its edge, 25 and cover sections each having tongues adapted to fit in one of the grooves in the partition and in the groove in one of the end pieces.

2. In a knockdown brooder, the combination with end pieces, of a partition, a cover 30 detachably connected to the end pieces and partition, a heating pipe, said partition having a passage for said pipe, and flaps 35 controlling access to said passage and serving to support the pipe therein.

3. In a knockdown brooder, the combination with end pieces, of a partition, a cover 40 detachably connected to the end pieces and partition, a heating pipe, said partition having a passage for said pipe and a doorway therein, and flaps between the passage and doorway for admitting the pipe to said passage and retaining it therein.

In testimony whereof I have signed my 45 name to this specification.

ERWIN MAURER.
